ATTORNEY:

UNITED STATES PATENT OFFICE.

CHARLOTTE E. PAGE, OF CHICAGO, ILLINOIS.

NECKTIE.

SPECIFICATION forming part of Letters Patent No. 331,535, dated December 1, 1885.

Application filed April 18, 1885. Serial No. 162,628. (Model.)

To all whom it may concern:

Be it known that I, CHARLOTTE E. PAGE, a citizen of the United States, residing at Chicago, in the county of Cook and State of Illinois, have invented certain new and useful Improvements in Neckties, of which the following is a specification.

This invention relates to an improvement in neckties; and it consists in the peculiar construction and arrangement of the same, substantially as will be hereinafter more fully set forth and claimed.

In order to enable others skilled in the art to which my invention appertains to make and use the same, I will now proceed to describe its construction and use, referring to the accompanying drawings, in which—

Figure 1 is a view of a tie made according to my invention. Fig. 2 is a detail view 20 of the knotted center piece. Fig. 3 is a rear view of the tie, and Fig. 4 is a diagram of the manner of cutting out the main portion of my tie.

In the construction of the kind of neckties herein represented much material has heretofore been wasted in the manner of cutting, and in that portion of the tie which is commonly covered by the vest, and so hidden from sight.

30 In the construction of my tie I take a perfectly square piece of material and cut a small square out of one corner, and then cut it diagonally across from corner to corner, as shown in Fig. 4. I thus cut out pieces exactly alike, and do not waste any of the material,

as the small corner removed in cutting is of such a form as to be readily utilized in other work. I place the two main parts of material, *a a*, together, as in Fig. 1, with their di-

agonally-cut edges overlapped, thus forming a triangular indentation at the center of the upper edge, which is filled with any desired center, but which I prefer to fill as follows: I take a strip of material, either the same as or 45 different from the main body of the tie, and tie it into an ordinary knot, as at *b*, which is puffed or bunched to obtain a better effect, as in Figs. 1 and 2, and this knot is sewed to the main body of the tie to fill the notched center.

50 The effect of this knot is also greatly heightened by the twisting of the ends after being passed through the loop and before being drawn up,

as this gives a twisted appearance to the face of the knot when finished, as will be seen in the drawings. The neck-strap *c* of the usual 55 form is then secured, the securing-pin *d* inserted, and the device is finished.

Such a tie not only presents a novel and pleasing effect, but is made with less material than heretofore, the material being cut bias, 60 so that all parts are readily utilized. The knotted center piece is quickly and easily formed, and is applicable to any form of tie that has the notched upper edge which it can fill.

In some cases, to fill and stiffen the upper edge of the tie, I form or tie the knot around the strip of card-board or cloth, as at *e* in Fig. 3, and this is secured in place with the knot to stiffen and aid in retaining the upper edge in 70 shape.

In any case I use the rear side of the knot *b* as a keeper for the end of the neckband *c*, and thus dispense with the usual shield used for this purpose, the neckband being simply 75 drawn through the knot and secured by the pin, as indicated in Fig. 3.

It will be noticed that the main body of the tie is drawn down to an approximate point, which gives this part of the article a very 80 symmetrical V-shaped appearance, and the diagonally-cut edges of the material run in a vertical line down the center, as shown; but the V shape at the bottom may be dispensed with, if desired, without departing from the 85 spirit of my invention.

The twisted ends of the knot *b* are secured to the main body of the tie or to the rear portion of the knot by sewing or otherwise. This insures the twisted ends to remain so, and retain the puffed appearance of the knot.

Having thus fully described my invention, what I claim as new, and desire to secure by Letters Patent, is—

1. As an improved article of manufacture, 95 a flat tie or neckscarf having its center piece composed of a strip of material tied in a knot, with the ends of said strip twisted after being passed through the loop of the said knot to give a twisted and bunched appearance to the 100 knot when drawn tight, and secured in such twisted position beneath the body of the scarf, substantially as shown and described, and for the purpose set forth.

2. As an improved article of manufacture, a flat tie or neckscarf having the main body composed of two pieces of material, *a a*, whose meeting edges are cut on a line diagonal to the lines bounding the right angular outer corners of the scarf, and the said scarf edges overlapping one upon the other in a vertical line down the center of the said scarf, substantially as shown and described, and for the purpose set forth.
3. In a neckscarf, the pieces *a a*, formed and secured together to form a V-shaped main

portion, as specified, in combination with the center piece, *b*, having the knotted appearance herein described, the neck-strap *c*, and pin *d*, 15 all constructed and combined substantially in the manner and for the purpose set forth.

In testimony whereof I affix my signature in presence of two witnesses.

CHARLOTTE E. PAGE.
